UNITED STATES PATENT OFFICE.

DANIEL W. BONNELL, OF PHILADELPHIA, PENNSYLVANIA.

WING CONTROL FOR FLYING MACHINES AND SAFETY DEVICE THEREFOR.

Application filed January 24, 1923. Serial No. 614,511.

To all whom it may concern:

Be it known that I, DANIEL W. BONNELL, a citizen of the United States, residing in the city and county of Philadelphia, State of Pennsylvania, have invented a new and useful Wing Control for Flying Machines and Safety Devices Therefor, of which the following is a specification.

My invention relates to a novel construction of a flying machine and more particularly to the actuation of the wings thereof which are mounted on the body of the machine for movement after the manner of the wings of a bird, and a novel gate, cross head, or wing actuating device, and comprises a novel construction of frame, gate, cross head, or wing actuating device and a novel construction of a support or guide therefor, said cross head serving as a wing control 10 and being provided with lateral slots by which the inner ends of the arms carrying the wings are actuated, means being provided for reciprocating said cross head or wing control by a connecting rod connected to the crank or fly wheel of an internal combustion engine or other motor, whereby the machine will rise directly from the ground.

It further consists of a novel manner of assembling and actuating the cross head or wing actuating device and the inner ends of the arms which support the wings.

It further consists of a novel construction of wings.

It further consists of a novel construction of a safety device secured to the floor of the flying machine, and means for instantly causing the same to open when desired.

It further consists of other novel features of construction, all as will be hereinafter fully set forth.

Referring to the drawings:

Figure 1 represents a front elevation of a flying machine embodying my invention, the safety device being shown closed and the wings being shown in the upward position.

Figure 2 represents a plan view of Figure 1, certain of the parts seen in Figure 1 being omitted for the sake of clearness of illustration.

Figure 3 represents a front elevation of the reciprocating gate, cross head or wing control device.

Figure 4 represents a plan view of one of the wings in detached position.

Figure 5 represents a section on line 5—5 Figure 4.

Figure 6 represents a side elevation of a safety device detached from the flying machine and in open position.

Figure 7 represents on an enlarged scale 60 a detail view of the upper portion of the safety device to be hereafter referred to.

Similar numerals of reference indicate corresponding parts.

1 designates my novel construction of flying machine, the same comprising a suitable frame work or light skeleton frame, composed of the base member or floor 2, and the outer side wing supports 3, through the upper ends of which pass the bolts 4, said 65 bolts passing also through the arms 5 of the wings 6 at the points 7, see Figure 4. The arms 5 are preferably constructed of channel beams or U shape in cross section. The inner ends of the wing arms 5 are slotted or 70 bifurcated as indicated at 8, and within the forks of said arms, I locate the lower outer portions 9 of the frame, cross head or wing control 10.

The lower outer ends of the cross head 10 80 are provided with the elongated horizontal or lateral slots 11 and the connection between each of the wing arms 5 and said slots is made by means of the bolt 12, which carries the friction roller 13, see Figure 4, it being understood that said roller is reciprocated in the slot 11 in the cross head 10, as the latter is moved up and down, so that friction is reduced to a minimum. The cross head 10 is 85 provided at its sides with the T shaped parallel upright guides 14 (see Figure 2) which are guided in the similarly shaped ways in the uprights 15 (see Figures 1 and 2) said ways 15 being supported at their bottom 90 ends upon the base member or floor 2, and being tied together at their upper ends by the cross piece 16, so that a very firm and rigid guide structure for the wing control is produced.

The gate, cross head or wing control 10 is 100 reciprocated by means of the connecting rod 19, whose upper end is connected to said cross head by a pin 20, which passes through the hole or bearing 21 in the lower member 16 of the cross head, the lower end of said connecting rod being connected by the crank pin 22 to the fly wheel or disc 23, which is mounted on the shaft 24, which is rotated by a gasoline motor or an internal combustion engine of any conventional or standard 110 type (not shown).

It is well known that in a device of this

character, it is essential that the frame work be as light as possible, so that a minimum of weight as well as a maximum of strength is obtained, and it is also desirable that the movements of the parts and the friction therebetween also be reduced to a minimum.

It will be apparent from the foregoing, that the number of parts composing my invention is reduced to a minimum, since I merely employ the skeleton frame composed of the base or floor member 2, outer wing supports 3 and the inner uprights or guides 15, which are secured at their lower ends to the floor 2 and tied together at their upper ends by the top cross piece 16. The cross head or wing control 10 is also designed so as to give a maximum of strength with a minimum of weight.

It will be apparent that the engine shaft 20 and the crank disc or fly wheel 23 are rotated as a unit and that the throw of the connecting rod 19 will cause the cross head or wing control 10 to reciprocate from the position seen in full lines in Figure 1 to the position seen in dotted lines in said figure, whereupon the wings 6 will be continuously oscillated in such a manner as to simulate the flying of a bird, their oscillation being caused by the continuously rotating mechanism having a connection therewith.

I have deemed it unnecessary to show or describe in detail the fuselage or the seats for the operator or the steering mechanism, as it will be evident that these elements may be constructed and arranged in accordance with any approved or conventional design, and the wing supports 3 may be braced or reinforced with respect to the floor 2 and the uprights 15 in any suitable manner.

It will be understood that the frame-work, wing control and their adjuncts may be constructed of any suitable light metal, as aluminum or the like and the outer frame work of the wings 6 is also preferably made of light tubing or preferably, channel beams, as indicated at 25, which is reinforced by transverse and longitudinal channel beams, as indicated at 26, 27, 28 and 29, the outer portions of each wing arm 5 being connected to said transverse channel beams 26 to 29, as will be understood from Figure 4.

The front, bottom and side of each wing is concave interiorly which concavity tapers to an almost straight or flat surface at the outer bottom side, and the frame of the wings is further braced and reinforced by the longitudinal side channel beams 26, which are arranged at each side of the arm 5, and tied together at their outer ends by the transverse outer channel beam 27.

The wing frame is further reinforced by the diagonal channel beams 28, all the channel beams being preferably of aluminum or the like, and the whole structure being covered with canvas, silk or the like.

My novel safety device 30, which is shown in closed position in Figure 1 and in open position in Figure 6, comprises the hollow rod or tube 31, whose lower end may pass through the floor 2 at one side of the wing 70 operating mechanism, and is secured by the upper and lower nuts 32 and 33, as seen in Figure 1.

The rod 31 has a collar 34 secured thereto by the set screw 35 and above said collar is 75 the runner 36, which, when in its lowest position (seen dotted in Figure 6) is engaged by the hook 37 of the trigger 38, which is fulcrumed at 39 to the fixed collar 34, and terminates at its lower end in the handle 40, which is within the convenient reach of the operator. Above the runner 36 is the upper fixed collar 41 held in position by the set screw 42.

43 designates a lower spring interposed 85 between the collar 34 and the runner 36 and 44 designates an upper spring interposed between the top of the runner 36 and the upper fixed collar 41. 45 designates the stretchers common to the runner 36 and the 90 ribs 46, which latter carry the cover 47. The upper spring 44 has one end attached to the runner as indicated at 48, see Figure 7, and its upper end is attached to the fixed collar 41, as indicated at 49 (see Figure 6). 95 The rod 31 is preferably hollow, and has the slot 50 therein, see Figure 7, through which protrudes the catch 51, which is pivotally supported at 52 and is normally pressed outwardly by the spring 53 (see Figure 7), so 100 that when the runner 36 is in its upper position, the catch will engage it and keep the parts in the open position seen in Figure 6 in full lines.

It will be apparent that when the safety device is closed, it will appear as seen in Figure 1, and when the handle 40 is actuated, the trigger will appear as seen in Figure 6, and due to the expanding action of the lower spring 43 and the contractile action of the upper spring 44, the parts will instantly open into the position seen in full lines in Figure 6, it being evident that it is essential for the safety device to operate instantaneously when its use becomes necessary.

The rod 31 of the safety device and the upper portion of the mechanism thereof are positioned at one side of the wing operating mechanism at such a point as not to affect 120 the center of gravity of the machine.

It will be apparent that the safety device seen in Figures 1 to 6 can be readily removed from the machine when it is desired to store the latter by taking off the bolts 32 125 and 33.

It will be understood that the tube, ribs and the trigger of said safety device are preferably made of duralumin; the springs are made of steel; the covering may be can- 130

vas, aluminum or silk; the cables or ropes on the edge of the edge of the cover may be made of twisted strands of duralumin or plain hemp rope.

5 It will now be apparent that I have devised a novel and useful wing control for flying machines which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what 20 I claim as new and desire to secure by Letters Patent, is—

1. In a flying machine, a framework, composed of a floor and outer wing supports, wings having arms pivotally mounted in the 25 upper portion of said supports, inner uprights mounted on said floor and provided with vertically extending ways, a cross head having a plurality of vertical T-shaped guides thereon engaging similarly shaped 30 vertical slots in said ways, horizontal slots in the lower outer portions of said cross head, connections common to the inner ends of said arms and said slots and means for actuating said cross head up and down to 35 oscillate said wings.

2. In a flying machine, a framework, composed of a floor and outer wing supports, wings having arms pivotally mounted in the upper portion of said supports, inner uprights mounted on said floor and provided with vertically extending T shaped ways, a cross head having T shaped vertical guides thereon engaging similarly shaped slots in said ways, horizontal slots 40 in the lower outer portions of said cross head, pivotal connections common to the inner ends of said arms and said slots, and means for reciprocating said cross head to oscillate said wings, said means comprising an engine shaft, a fly wheel mounted thereon and a connecting rod eccentrically connected at its lower end to said fly wheel and pivotally connected at its other end to said cross head.

55 3. In a flying machine, a framework com-

prising a floor and outer wing supports, wings having channelled arms pivotally mounted in the upper ends of said supports, a wing control device, comprising a frame, having horizontal top and bottom members 60 and upwardly converging sides, and having horizontal slots in its lower portions, connections common to the inner ends of said arms and said slots, inner vertical uprights provided with T-shaped ways, T shaped 65 vertical guides mounted on said frame, an engine shaft, a fly wheel mounted on said shaft and a connecting rod having its lower end eccentrically connected to said fly wheel and its upper end pivotally connected to the 70 lower portion of said frame.

4. In a flying machine, upright parallel T shaped ways, a cross head having parallel vertical T shaped guides, lateral slots in the lower portion of said cross head, wing arms 75 pivotally supported and forked at their inner ends, anti-friction rollers in said slots, bolts passing through said rollers and the ends of said wing arms, an engine shaft having a fly wheel thereon, and a connecting rod 80 common to said fly wheel and cross head.

5. A wing for a flying machine composed of an outer channelled frame, a central longitudinal arm composed of a light channel beam extending longitudinally of said frame, transverse channel beams secured to said frame and central arm, side longitudinally extending channel beams also secured to said transverse channel beams, and diagonal channel beams secured to the outer wing 90 frame and a cover for the latter.

6. A wing for a flying machine composed of an outer pivotally supported frame, a central arm composed of a light channel beam extending longitudinally of said frame, transverse channel beams secured to said central arm and outer frame, side longitudinally extending channel beams also secured to said transverse beams, diagonal channel beams secured to the outer wing 95 frame, a cover for said wing, the latter being concaved on its under side, and said central arm having a fork at its outer end adapted to be connected with a vertically 100 moving cross head.
